(57) **CLAIM**

The ornamental design for a pipe clamp with a threaded extension, as shown and described.

DESCRIPTION

FIG. 1 is a perspective view of a pipe clamp with a threaded extension according to at least one embodiment;

FIG. 2 is a front elevation view of the pipe clamp with the threaded extension of FIG. 1;

FIG. 3 is a rear elevation view of the pipe clamp with the threaded extension of FIG. 1;

FIG. 4 is a right side elevation view of the pipe clamp with the threaded extension of FIG. 1;

FIG. 5 is a left side elevation view of the pipe clamp with the threaded extension of FIG. 1;

FIG. 6 is a top plan view of the pipe clamp with the threaded extension of FIG. 1;

FIG. 7 is a bottom plan view of the pipe clamp with the threaded extension of FIG. 1;

FIG. 8 is a perspective view of the pipe clamp with the threaded extension of FIG. 1 in an environment of use;

FIG. 9 is a perspective view of a pipe clamp with a threaded extension according to another embodiment;

FIG. 10 is a front elevation view of the pipe clamp with the threaded extension of FIG. 9;

FIG. 11 is a rear elevation view of the pipe clamp with the threaded extension of FIG. 9;

FIG. 12 is a right side elevation view of the pipe clamp with the threaded extension of FIG. 9;

FIG. 13 is a left side elevation view of the pipe clamp with the threaded extension of FIG. 9;

FIG. 14 is a top plan view of the pipe clamp with the threaded extension of FIG. 9;

FIG. 15 is a bottom plan view of the pipe clamp with the threaded extension of FIG. 9; and,

FIG. 16 is a perspective view of the pipe clamp with the threaded extension of FIG. 9 in an environment of use.

(Continued)

The broken lines are included for the purpose of illustrating environment and portions of the pipe clamp with the threaded extension that form no part of the claimed design.
